UNITED STATES PATENT OFFICE.

WILLIAM P. KRAUSE, OF CHICAGO, ILLINOIS, ASSIGNOR TO HANNA ENGINEERING WORKS, OF CHICAGO, ILLINOIS, A CORPORATION OF ILLINOIS.

RIVETER.

1,404,126.

Specification of Letters Patent. Patented Jan. 17, 1922.

Application filed February 13, 1919. Serial No. 276,776.

To all whom it may concern:

Be it known that I, WILLIAM P. KRAUSE, a citizen of the United States, residing at Chicago, in the county of Cook and State 5 of Illinois, have invented certain new and useful Improvements in Riveters, of which the following is a specification.

This invention relates to improvements in riveters, and has for its object to provide a 10 new and improved form of riveter construction, which may be applied to yoke and lever compression type riveters, of the kind known in the trade as "Hanna" riveters, to enable them to handle such work as riveting 15 channel and I-beams.

Hitherto special devices and machines have been required to handle the type of work mentioned, where projecting flanges render it impossible for the riveting dies or 20 stakes to reach the points of riveting, especially where small work is being handled.

My invention provides a construction which will overcome the deficiency of ordinary riveting machines and enable it to handle 25 this type of work. This and other objects of the invention will be more fully set forth and described in the following specification, taken in connection with the accompanying drawings, in which—

30 Figure 1 is a side elevation of a Hanna type of riveter portions being broken away for clearness, with my invention applied thereto;

Fig. 2 is a vertical section through portions 35 of the construction shown in Fig. 1, showing a detail of the application of my invention and means for securing the lower die or stake in place;

Fig. 2^a is a view similar to Fig. 2, showing 40 the means for compensating for wear of the lower die;

Fig. 3 is a plan view of the construction shown in Fig. 2;

Fig. 4 is a transverse cross section, taken 45 on the line 4—4 of Fig. 2^a, the locking pin being shown in elevation;

Fig. 5 is a front elevation of my machine, showing a modified arrangement of the lower stake;

50 Fig. 6 is a side elevation of the same; and

Fig. 7 is a side elevation of a compression lever type of riveter, showing my invention applied thereto, portions thereof being 55 shown in section.

Like numerals refer to like elements throughout the drawings, in which 10 designates generally the yoke of a riveter of the Hanna type, the operation and general construction of which form no part of my present invention, and which needs no description herein. Extending through the upper jaw X of the yoke is the usual movable or reciprocable die screw 11, carrying the upper die 12. In the usual construction of this 65 type of riveter a co-acting stationary vertical die is located in the lower stake or jaw Y of the yoke beneath the moving die; but I replace this in my invention by a lower auxiliary stake casing, generally indicated 70 by the numeral 13, consisting of a base plate 13^a, secured by bolts 13^b, or the like, to the lower stake Y, and in which is fitted the lower auxiliary stake 14 constructed with the rivet cup 14^d. In the form shown in Figs. 75 1, 2, and 4 the lower auxiliary stake 14 is provided with a flattened surface 14^a, with which co-acts the flattened surface 15^a of a locking pin 15, which extends transversely through cross apertures in the casing 13, as 80 shown in Figs. 2, 3, and 4, respectively. The locking bolt 15 is provided with the head 15^b, as shown in Fig. 4, which, contacting with the lower auxiliary stake 14, properly seats the locking pin in assembled relation 85 to same, the flattened surfaces of both members being in contact, as shown in Fig. 2, for example.

In the form of lower auxiliary stake shown in the drawings, Figs. 1, 2, 2^a, 3 and 90 4, in order to provide a thrust surface for the lower end of the same, a block 16 is provided, of contour to fit the bore of the casing 13, and having one face inclined so as to lie upon the upper surface of the lower stake 95 Y of the yoke, and another to lie in a plane at right angles to the axis of the bore of the casing 13, so that the base of the lower auxiliary stake will contact therewith.

At its upper end the lower auxiliary stake 100 14 is cut away, as indicated by numeral 14^b, and cut off to form the top face 14^c, in which is provided the die cup 14^d.

In my construction, as shown, it will be apparent that the lower auxiliary stake 14, 105 by virtue of its inclination, will fit between the flanges of a channel beam, such as indicated by letter A, see Figs. 1 and 2, beneath the upper flange thereof, to permit riveting of a flat, angle, or other strip thereto, which 110

function is not possible where vertical stakes are used, as would be obvious from an examination of the drawings. Otherwise, in machines of this type, the only kind of channel or I-beam structures which may be handled are those in which the distance between the flanges is greater than the distance from the top of the lower vertical riveter die to the bottom of the lower stake of the riveter.

As the lower auxiliary stake wears down, provision may be made for such wear, by removing it and inserting washers or shims 16' between the base of the same and the top 15 of the block 16, and the upper end may be dressed off, as indicated by the dotted lines in Fig. 2^a, to bring the rivet or die cup or depression into proper alignment with the upper or movable die, so that the life of the 20 lower auxiliary stake can be prolonged.

In Figs. 5 and 6 I have shown a different form of construction, in which the riveter 10' is made more compact, and especially constructed to utilize the inclined lower 25 auxiliary stake or jaw construction. In this embodiment the riveter yoke is provided with the inclined lower stake or jaw 20, centrally bored as indicated in dotted lines in Fig. 6, the socket being designated by numeral 20^a. The bore 20^a is shouldered to provide a thrust shoulder for the shoulder 21^a of the lower auxiliary stake 21, which is reduced in diameter below such shoulder 21^a, as indicated by numeral 21^b. A locking 30 pin 22 is provided, the same having a flattened surface to co-act with the flattened surface 21^c of the lower auxiliary stake 21, as in the construction shown in Figs. 2 and 4, the main difference being that a set screw 40 23, extending through a suitable threaded aperture in the lower stake 20, contacts with the locking pin 22 to maintain the same in proper position. This construction is shown in section in the modified form of riveter in 45 Fig. 7. When it is necessary to extend the lower auxiliary stake to compensate for the redressing necessitated by wear, annular washers, such as 21^d—see Fig. 7—which take up such extension, may be provided, such 50 washers being mounted around the portion 21^b of the lower auxiliary stake 21, between the shoulder 21^a of the lower auxiliary stake 21 and the corresponding shoulder of the bore 20^a.

55 The construction just described is desirable when constructing a riveter especially for channelled work, whereas that shown in Figs. 1-4 permits the adaptation of the old style vertical die machines to handle the channelled form of work.

In Fig. 7 I have shown my invention as applied to another type of riveter, known as the compression lever type, where there is provided a fixed lower stake or jaw 30 60 and a movable upper jaw 31, each of said

jaws being provided with bores 32, similar to that shown and described in connection with Fig. 6; the auxiliary stakes 21 being the same as in Fig. 6. In this form of machine I provide two inclined dies 21, one 70 of these dies corresponding to the auxiliary stake of the previously described form, whereby the riveting of one channel member to another may be accomplished, as shown in Fig. 7, where two channel beams B and 75 C are shown as being riveted together, thus illustrating the advantage of the construction.

It will be seen from an examination of the structure shown in Fig. 7, that both 80 auxiliary stake members in this embodiment are arranged at an angle with respect to both the horizontal and vertical, and that the included angle therebetween is less than a straight angle, or 180°. In other words, 85 both are normally arranged at an angle with respect to the operative axis, that is, in the embodiment shown, the axis of the rivet being riveted.

It will be obvious that my invention is 90 susceptible to modifications and improvements, and I do not wish to be restricted thereto, except as defined in the appended claims.

What I claim is:—

1. In a device of the class described, jaw members, a riveting member carried by one of said jaws, the other thereof being provided with an inclined socket or bore, and an auxiliary stake mounted in said socket and inclined with respect to said riveting member.

2. In a device of the class described, jaw members, a riveting member carried by one of said jaws, the other thereof being provided with an inclined socket or bore, an auxiliary stake mounted in said socket and inclined with respect to said riveting member, and means to retain said auxiliary stake in proper relation to said riveting member.

3. In a device of the class described, jaw members, a riveting member carried by one of said jaws, the other thereof being provided with an inclined socket or bore, an auxiliary stake mounted in said socket and inclined with respect to said riveting member, and means to retain said auxiliary stake in proper relation to said riveting member, said means comprising a locking pin.

4. In a device of the class described, jaw members, a riveting member carried by one of said jaws, the other thereof being provided with an inclined socket or bore, an auxiliary stake mounted in said socket and inclined with respect to said riveting member, and means to retain said auxiliary stake in proper relation to said riveting member, said means comprising a locking pin, said auxiliary stake and locking pin being provided with co-acting flat surfaces.

5. In a device of the class described, a stake, an auxiliary stake carried thereby, said first-named stake being apertured or socketed, said auxiliary stake being mounted in said socket, and means to extend said auxiliary stake member in said socket and maintain the same in extended position.
6. In a device of the class described, a stake, an auxiliary stake carried thereby, 10 said first-named stake being apertured or socketed, said auxiliary stake being mounted in said socket, and means to extend said auxiliary stake member in said socket and maintain the same in extended position, said 15 means comprising shims.
7. In a compression type of riveter, a pair of jaw members movable relatively into and out of riveting position, and auxiliary rivet-engaging and forming members carried by 20 said jaws and each axially inclined with re-

spect to the axis of a rivet upon which they are acting.

8. In a compression type of riveter, a pair of jaw members movable relatively into and out of riveting position, and auxiliary 25 rivet-engaging and forming members carried by said jaws, said auxiliary members being axially inclined with respect to the horizontal and vertical.

9. In a compression type of riveter, a pair of jaw members movable relatively into and out of riveting position, and auxiliary 30 rivet-engaging and forming members carried by said jaws and each axially inclined with respect to the axis of a rivet upon 35 which they are acting, said auxiliary members being adjustably extensible.

In testimony whereof, I have subscribed my name.

WILLIAM P. KRAUSE.
